UNITED STATES PATENT OFFICE.

WALTER FERRIS, OF SOUTH MILWAUKEE, WISCONSIN, ASSIGNOR TO BUCYRUS COMPANY, OF SOUTH MILWAUKEE, WISCONSIN, A CORPORATION OF WISCONSIN.

PROPELLED MECHANISM FOR LOCOMOTIVE-CRANES AND THE LIKE.

1,273,472.

Specification of Letters Patent.

Patented July 23, 1918.

Application filed March 1, 1917. Serial No. 151,860.

To all whom it may concern:

Be it known that I, WALTER FERRIS, a citizen of the United States, residing at South Milwaukee, in the county of Milwaukee and 5 State of Wisconsin, have invented a certain new and useful Improvement in Propelling Mechanism for Locomotive-Cranes and the like, of which the following is a specification.

10 My invention relates to locomotive cranes and particularly to propelling mechanism therefor. It is understood, of course, that locomotive cranes are, when in operation, expected to propel themselves from place to 15 place but that when they are being brought to the scene of operation they are ordinarily coupled into a train of cars and hauled by locomotive in the usual way.

One object of my invention is to provide 20 a new and improved traction or propelling mechanism whereby the crane engine may propel the vehicle about while it is at work. Another object is to provide a new and improved connection between the engine and 25 the running gear such that when the crane is to be propelled by the locomotive as part of a train, its self-propelling mechanism may be completely disconnected so that there will be no drag on the car and no resistance 30 to the traction of the locomotive. This is also desirable in order that the wear and tear on the propelling mechanism which ordinarily operates at a low rate of speed will not be excessive as it will be if the propelling mechanism itself were driven by the movement 35 of the wheels at the high speed at which the wrecking crane is moved from place to place in times of emergency. One object, therefore, is to provide a clutch arrangement 40 whereby the slow speed propelling mechanism may be entirely disconnected with a minimum of difficulty at the will of the operator.

It is understood, of course, that these locomotive cranes frequently travel over temporary and irregular tracks and another object of my invention is, therefore, to provide a universal joint between the driving mechanism and the car axle such that any 50 local irregularities of the track will not affect disadvantageously the driving gear.

My invention is illustrated more or less diagrammatically in the accompanying drawings wherein—

55 Figure 1 is a section through a part of

the wrecking car showing my invention partially in section, partially in elevation;

Fig. 2 is a section through the central portion of the car at right angles to the section line of Fig. 1; 60

Fig. 3 is a section through a car wheel showing my universal joint when the axle is in a normal plane;

Fig. 4 is a similar section showing the 65 axle inclined.

Like parts are indicated by like characters in all the drawings.

A is a car frame. A¹ is the usual type of turn-table supporting bed plate or frame mounted in the car frame. A² is a supporting web frame extending inwardly from the base frame A¹ and terminating in a cup A³. It is understood that A⁴, A⁵, and A⁶ 70 are the tracks upon which the turntable travels being supported by rollers not here shown. A⁷ is the ordinary type of turntable adapted to be supported on tracks A⁴, A⁵, A⁶ as indicated adapted to be swung about such tracks by means of a pinion not shown, engaging the gear A⁸. This turntable is 80 provided with a cylindrical lug A⁹ engaging the cup A³ for the purpose of centering it on the frame.

B is a drive shaft rotatably mounted in a bearing sleeve B¹ in the part A⁹ extending down through a bearing sleeve B² in the bottom of the cup A³. It carries on its lower end a drive pinion B⁴ and on its upper end a drive pinion B⁵ both rigidly fastened to it. B⁶ is an engine shaft carrying 90 a clutch B⁷ splined thereon in opposition to a clutch B⁸ on a driving pinion B⁹ in mesh with the gear B⁵ so that by manipulation of this clutch power may be transmitted from the engine shaft B⁶ to rotate the pinion B⁴. 95

C, C¹ are pinions in mesh with the pinion B⁴. They are mounted rigidly on the shafts C², C³ in bearings C⁴, C⁵ on the car frame. At their lower ends each one of them carries a mitered pinion C⁶, the pinion C⁶ being 100 in mesh with a gear C⁷ on the sleeve C⁸. The sleeve C⁸ is rotatably mounted in a bearing C⁹ on a bracket C¹⁰ depending downwardly from the car frame.

The sleeve C⁸ is hollow and through it 105 passes the car axle D adapted to engage car journals at its ends not here illustrated. This axle is supported on the car wheels D¹, D² which travel along the rails D³, D⁴. D⁵ is a flange on the sleeve C⁸. It carries a 110

ring D^4 rotatably mounted on pins D^5 . D^6 ,
 D^7 are driving links pivoted on the pins D^8
on one side of the ring D^4 . These driving
links are adapted to be located one on either
5 side of the axle D and are held in parallelism
by their pivoted connection on the pins D^8
and by their pivot mounting at their other
ends on a pin D^9 . This pin D^9 furnishes
a pivot connection between these links and
10 a rigid lever D^{10} .

10 This rigid lever D^{10} is forked and engages
lugs or pins E projecting outwardly from
opposed sides of a clutch ring E^1 which
15 clutch ring is rotatably mounted on the axle
 D by means of a sleeve E^2 and held in position
by the collar E^3 and rings E^4 . E^5 is a
clutch splined on axle D in opposition to a
20 clutch E^6 on the side of the clutch collar E^1
so that by manipulation of this clutch the
axle and sleeve may be discontinuously
25 connected through the clutch, the pivot arms
and the pivotally mounted ring. It will be
understood, of course, that the pivot arms
and their associated parts form a universal
30 joint between the sleeve and the axle so that
power may be transmitted no matter what
the position of the parts.

When there is ample time available and
30 no objections to having a man go under the
car, as for instance, when the crane is about
to make a long journey, means are provided
whereby the lever D^{10} may be disengaged
35 from the lug or pin E on the clutch ring E^1
and may be swung back until the lug E^7 on
the lever D^{10} is in register with the lug E^6
40 on the flange D^8 on the sleeve C^8 . The pin
is then passed through the two lugs and this
holds the two members on the universal joint
firmly in position on the flange D^8 thus com-
45 pletely disconnecting the universal joint
and permitting normal operation and move-
ment of the crane car without any reference
to the universal joint whatever. But for
50 ordinary purposes it is sufficient to open the
clutch when the car can travel, the axle ro-
tating with respect to the clutch and all the
driving mechanism except that part of the
clutch itself which is splined to the axle
55 will then be at rest. By this arrangement
the operator has merely to throw the clutch
60 to be sure that the parts will be ready for
operation.

I have, of course, not illustrated in detail
55 all the parts of the crane or the car upon
which it is mounted. I have merely sug-
gested certain parts necessary to illustrate
the arrangement and operation of my device.
Obviously my invention might be applied to
60 many different types of locomotive cranes
and the way in which it is arranged in such
cranes is subject to wide variations without
in any way departing from the spirit of the
invention. It must be understood, there-
65 fore, that my drawings are in a sense
diagrammatic.

I claim:—

1. A propelling gear comprising a driv-
ing sleeve surrounding but not touching a
driven axle, a universal joint connecting said
driving sleeve with a clutch member revolu-
70 bly mounted upon said axle and a jaw clutch
whereby said sleeve may be connected to or
disconnected from the axle.

2. A propelling gear for driving an axle
comprising a sleeve surrounding but not
75 touching the axle, a clutch member revolu-
bly mounted upon the axle, a disconnectible
universal joint whereby the sleeve drives the
clutch member and disconnecting means
80 whereby the clutch member drives the axle.

3. In a revolving crane structure which
comprises a car body, a revolving frame and
an axle, a propelling gear arrangement com-
85 prising a source of power mounted on the
revolving frame, a bevel pinion shaft con-
centric with the pivot axis of the revolving
mechanism and carrying a pinion at its lower
90 end, a driving sleeve surrounding the axle
but mounted upon the car body and an in-
clined shaft carrying near its two ends bevel
gears meshing respectively with the gears on
95 the vertical pinion shaft and on the driving
sleeve.

4. In a revolving crane structure which
comprises a car body, a revolving frame and
100 an axle, a propelling gear arrangement com-
prising a source of power mounted on the
revolving frame, a bevel pinion shaft con-
centric with the pivot axis of the revolving
105 mechanism and carrying a pinion at its lower
end, a driving sleeve surrounding the axle
but mounted upon the car body, an in-
clined shaft carrying near its two ends bevel
110 gears meshing respectively with the gears on
the vertical pinion shaft and on the driving
sleeve, and a universal driving connection
between the sleeve and the axle.

5. In a revolving crane structure which
comprises a car body, a revolving frame and
115 an axle, a propelling gear arrangement com-
prising a source of power mounted on the
revolving frame, a bevel pinion shaft con-
centric with the pivot axis of the re-
volving mechanism and carrying a pinion,
120 at its lower end, a driving sleeve surround-
ing the axle but mounted upon the car
body, an inclined shaft carrying near its
two ends bevel gears meshing respectively
125 with the gears on the vertical pinion shaft
and on the driving sleeve, and a detachable
universal joint connecting the sleeve to the
axle.

6. In a revolving crane structure which
comprises a car body, a revolving frame and
130 an axle, a propelling gear arrangement com-
prising a source of power mounted on the
revolving frame, a bevel pinion shaft con-
centric with the pivot axis of the re-
volving mechanism and carrying a pinion
at its lower end, a driving sleeve surround-

- ing the axle but mounted upon the car body, a clutch collar revolubly mounted upon the axle, a universal joint connecting the sleeve to the clutch collar and a clutch member mounted upon the axle through which the clutch collar drives the axle. 5
7. A propelling gear comprising a driven axle, a driving sleeve flanged at each end, surrounding but out of contact with it a 10 driving pinion, a gear on one of said flanges in mesh with it, a clutch on the axle, a universal joint between the clutch and the other flange.
8. A propelling gear comprising a driven 15 axle, a driving sleeve flanged at each end, surrounding but out of contact with it a driving pinion, a gear on one of said flanges in mesh with it, a clutch on the axle, a universal joint between the clutch and the 20 other flange the universal joint being detachable and means for holding the parts of the universal joint in position to permit rotation of clutch and sleeve without interference.
- 25 9. A propelling gear comprising a driven axle, a driving sleeve flanged at each end, surrounding but out of contact with it a driving pinion, a gear on one of said flanges in mesh with it, a clutch on the axle, a universal 30 joint between the clutch and the other flange the universal joint comprising a member pivoted for rotation on the flange on an axis perpendicular to the axis of the truck arms pivoted on such member extending upwardly one on either side of the axle and a pivot member interposed between the clutch and the other end of said arms. 35
10. A propelling gear comprising a driven axle, a driving sleeve flanged at each 40 end, surrounding but out of contact with it, a driving pinion, a gear on one of said flanges in mesh with it, a clutch on the axle, a universal joint between the clutch and the other flange the universal joint comprising 45 a member pivoted for rotation on the flange
- on an axis perpendicular to the axis of the truck arms pivoted on such member extending upwardly one on either side of the axle and a pivot member interposed between the clutch and the other end of said arms, a 50 part on such pivot member and a part on the flange said parts being perforated and adapted to be in register with the universal joint when it is engaged and the arms sprung back against the flange whereby a 55 holding pin may pass through them.
11. A propelling gear comprising a driven axle, a driving sleeve surrounding but out of contact therewith a bearing for the driving sleeve and means for rotating it, a 60 clutch member on the axle and means for removably connecting the clutch member and the sleeve and means for holding such removably connecting means in inoperative position without interfering with the opera- 65 tion of the parts.
12. A propelling gear comprising a driven axle, a driving sleeve surrounding but out of contact therewith a bearing for the driving sleeve and means for rotating it, a 70 clutch member on the axle and means for removably connecting the clutch member and the sleeve and means for holding such removably connecting means in inoperative position without interfering with the opera- 75 tion of the parts said connecting means comprising a member pivoted on the sleeve connecting links pivoted on such pivot member a member pivoted on the clutch in pivoted connection with such connecting 80 links the connecting links being parallel and arranged one on either side of the axle.

In testimony whereof, I affix my signature in the presence of two witnesses this 28th day of February, 1917.

WALTER FERRIS.
